ARMCHAIR

Maija Ruoslahti, Espoo, Finland, assignor to
Joel Mitikka, Lahti, Finland

Filed Mar. 22, 1972, Ser. No. 237,246

Claims priority, application Finland Nov. 1, 1971

Term of patent 14 years

Int. Cl. D6—02

U.S. Cl. D6—70

FIG. 1

FIG. 2

FIG. 3

FIG. 4

FIG. 5

FIG. 6

FIG. 1 is a perspective view of an armchair showing the new design taken from in front to the side of the armchair;

FIG. 2 is a perspective view of the armchair of FIG. 1 taken from the rear and to the side of the armchair; FIG. 3 is a side elevation view of the armchair; FIG. 4 is a rear elevation view of the armchair; FIG. 5 is a front elevation view of the armchair; and FIG. 6 is a top plan view of the armchair.

I claim:

The ornamental design for an armchair, as shown and described.
